UNITED STATES PATENT OFFICE

MILTON A. POWERS, OF DETROIT, MICHIGAN, ASSIGNOR TO THE TIMKEN SILENT AUTOMATIC COMPANY, OF DETROIT, MICHIGAN, A CORPORATION OF MICHIGAN

ROTARY OIL BURNER

Application filed July 24, 1929. Serial No. 380,527.

This invention relates to rotary oil burners and has for its principal objects a simple and compact construction in which the fuel is evenly distributed around the firing zone of the combustion chamber and the proper amount of air for combustion is supplied to the fuel in the region of said firing zone. Another object is to prevent atomizing of the fuel in the distributor head. Another object 10 is an improved shutter construction for regulating the air flow. Other objects are fewness of parts, economy of design and reduced noise of operation. The invention consists in the rotary oil burner and in the parts and 15 combinations and arrangement of parts hereinafter described and claimed.

In the accompanying drawings, which form part of this specification and wherein like symbols refer to like parts wherever they 20 occur,

Fig. 1 is a vertical longitudinal section through a rotary oil burner embodying my invention; and

Fig. 2 is a plan view of said burner; and 25 Fig. 3 is a side elevation thereof.

The present rotary oil burner comprises a combined burner and hearth supporting frame A adapted to be positioned within the ashpit of a furnace (not shown). The supporting frame A preferably comprises a ring-like body portion 1, which is open on the front side of said frame and has three circumferentially spaced brackets 2 depending therefrom that are provided with vertical 30 openings adapted to slidably engage tubular supporting legs 3. The leg engaging brackets 2 of the supporting frame are provided with set screws 4, whereby the frame may be clamped to the supporting legs 3 in any desired position of its vertical sliding movement thereon. The tubular legs 3 are interiorly threaded to receive the threaded shank portion 5 of foot members 6 that are provided with rubber cushioning blocks 7. The foot 35 members 6 are provided with transverse openings 8 adapted to receive a pin wrench, whereby the foot members may be rotated relative to the supporting legs to secure a fine vertical adjustment of the supporting frame independent of the coarser adjustment afforded

by the sliding connection between said legs and said frame.

The main body portion 1 of the supporting frame A is provided with two diametrically opposed upstanding brackets 9 having horizontal top flanges 10 upon which is bolted the outstanding base flange 11 of a hearth ring 12. Arms 13 extend radially beyond the hearth ring 12 to the furnace wall with their inner ends resting on the top of the base flange 11 of said ring and terminating in downwardly offset portions 14 that extend through vertical openings or recesses 12a in said base flange and bear against the underside thereof, thereby anchoring the inner 60 ends of said arms to said hearth ring. Supported on the radially extending arms 13 of the supporting frame A is a sheet metal plate 16 upon which is built a hearth 17 of refractory material, which forms the floor of the combustion chamber of the furnace and has a suitable flame retaining ring 17a at the outer periphery thereof.

Mounted in the supporting frame A concentric with the ringlike body portion 1 75 thereof is an electric motor B comprising a casing 18 having oppositely disposed outstanding arms 19 provided with vertically elongated slots 20 adapted to receive cap screws 21 that are threaded into horizontal holes provided therefor in diametrically opposed vertical flanges or lugs 22 on the inner side of said body portion of said supporting frame. The motor B may be adjusted vertically relative to its supporting frame A 80 as far as the elongated slots 20 will permit by means of adjusting screws 23 that are threaded through vertical holes provided therefor in horizontal lugs 24 formed integral with said frame beneath the motor supporting flanges 22 thereof and abut at their upper ends against the lower edges of said flanges. Lock nuts 25 are provided for securing the motor adjusting screws 23 in the desired adjusted position.

The lower end of the armature shaft 29 of the motor B is journaled in a bearing 30 provided therefor in a lubricant chamber 31 formed in the lower end of the motor casing 18. The armature shaft is supported at its

lower end on a ball thrust bearing 32 seated in the lower end of the lubricant chamber 31. A pipe 33 is threaded into the chamber 31 for supplying lubricant thereto. The upper end of the armature shaft 29 is supported in a bearing 34 provided therefor in the upper end of the motor casing 18, which bearing is supplied with lubricant from a chamber 35 located therebelow by means of an oil wick 36. 5 A pipe 37 is threaded into the chamber 35 for supplying lubricant thereto.

10 Mounted on and rigidly secured to the upper end of the motor casing 18 is an oil cup C having a hub 39 through which the armature shaft 29 extends and a comparatively shallow annular recess 40 in its bottom adapted to be supplied with oil through an oil feed pipe 41 threaded into said cup. The flow of the oil to the annular recess 40 in the bottom of the oil cup C may be regulated 15 by any suitable means (not shown). The armature shaft 29 extends upwardly above the oil cup C and has the hub of a distributor head D rigidly secured thereto for rotation therewith. The distributor head is made in 20 the form of a hollow cone disposed with its small end down and extending into the oil cup C. The small lower end of the hollow cone-shaped distributor head has an annular plate 42 screwed thereto, which is provided 25 at its inner periphery with a series of annularly spaced picker blades or tabs 43 that extend downwardly to or slightly below the level of the oil in the annular recess 40 in the bottom of the oil cup C. The blades 43 30 rotate with the hollow distributor head D and are shaped and arranged to lift or pick up the oil from the annular oil recess 40 in the oil cup C and deposit it upon the lower 35 edge of the cone-shaped inner surface of said distributor head without being broken up or atomized. The centrifugal action of the rotating distributor head, together with the gradually increasing diameter of the 40 inner surface thereof, causes the oil to spread 45 out in a thin layer on the conical inner surface of said distributor head and advance toward the upper end thereof.

50 The oil upon reaching the upper end of the hollow cone of the centrifugal distributor head D is thrown radially outward therefrom to the firing ring 17a of the hearth 17 through a series of circumferentially spaced radially disposed flinger tubes 44 that extend upwardly and outwardly from the upper edge 55 of said head and terminate at their upper ends in horizontally disposed portions located at about the level of the firing ring 17a. The oil that is discharged from the flinger tubes 60 is not finely atomized but leaves the tip of said tubes in the form of a thin sheet and is evenly distributed around the firing ring 17a of the hearth in the form of fine drops.

65 Air for combustion is supplied to the oil deposited on the firing ring 17a of the

hearth by a fan E mounted on the upper end of the hub of the distributor head D. Said fan comprises a dished circular plate 45 that is perforated at its center to receive the armature shaft, and is clamped to the upper end 70 of the hub of the distributor head by means of a nut 46 threaded on the upper end of said shaft. The plate 45 of the fan is provided with a series of openings through which the flinger tubes 44 extend. The top plate 45 75 of the fan is provided at its periphery with a depending flange 47 having outstanding blades 48 struck from openings therein. It is noted that the fan blades 48 are located below the tips of the flinger tubes 44, whereby air 80 flows from said fan below the level of said tips and does not mix to an appreciable extent with the oil particles until it reaches the region of the firing ring of the hearth. With this arrangement, oil is distributed 85 around the periphery of the hearth without being atomized, with the result that its inflammability is reduced and the tendency for the flame to flash back towards the burner is eliminated.

90 The amount of air delivered by the fan E is regulated by means of a shutter F comprising a cylindrical tube 49, whose lower end has a slideable and rotatable fit in the upstanding annular flange of the metal hearth ring 12 and whose upper end fits within the depending peripheral flange 47 of said fan. The air shutter F is secured to the upstanding annular flange of the hearth ring 12 by means of threaded studs 50 that extend 95 through a series of elongated slots 51 in the cylindrical tube 49 of said shutter and are threaded into said upstanding flange. The slots 51 are disposed at an oblique angle to the axes of the shutter, whereby rotation of 100 the shutter causes it to move vertically across the openings in the peripheral flange of the fan and thus regulate the flow of air from the fan. An operating handle 52 projects 105 radially outward from the lower end of the shutter whereby it may be conveniently adjusted. An important advantage of this shutter construction is that it allows a full open intake to the fan at all times thus greatly increasing the maximum capacity of the 110 fan over that of other fans of the same size but with the conventional air intake having overlapping shutter surfaces. In fact, the air intake area is more than 200% of the maximum with the conventional design. 115 Another advantage lies in the fact that the air is evenly distributed from the periphery of the fan. Another advantage is that the shutter collar protects the inside burner parts against radiant heat from the combustion 120 chamber and it allows adjustment of the fan vertically in the firebox without chance for air leakage between fan and hearth ring.

125 The hereinbefore described oil burner is simple and compact in construction and com-

- paratively inexpensive to manufacture, the air shutter, fan, and distributer head may be removed and the legs raised, thus reducing the height of the device and enabling it to 5 readily pass through the opening in the ash-
pit. The legs may be then adjusted to bring the hearth ring to the proper elevation, after
which the air shutter, fan, and distributer
head may be placed in position and a fine
10 final adjustment obtained by adjusting the
foot portions of the legs. The oil and air
leave the burner at different elevations and
do not mix to an appreciable extent until
they reach the region of the firing ring at
15 the periphery of the hearth, thereby over-
coming the tendency for the flame to flash
back towards the burner. The shutter may
be adjusted to any desired position to regu-
late the flow of air without decreasing the
20 width of the fan openings, thereby securing
an even discharge of the air around the per-
iphery of the fan in all positions of adjust-
ment of the damper; and the construction of
25 distributer head secures an even distribution
and steady flow of oil to the flinger tubes
without breaking up or atomizing the oil.
- Obviously, the hereinbefore described oil
burner admits of considerable modification
without departing from the invention, and
30 I do not wish to be limited to the precise con-
struction shown and described.
- What I claim is:
1. A rotary oil burner comprising a sup-
porting member, an electric motor thereon,
35 an armature shaft for said motor, a cup
mounted on said motor and having a hub
portion sleeved on the armature shaft there-
of, means for feeding liquid fuel to said cup,
40 and a distributer head fixed to said shaft
with its lower end disposed in said cup, said
distributer head having an inverted cone-
shape chamber therein communicating at its
45 bottom with the interior of said cup, said
distributer head chamber being provided at
its upper end with a series of circumferential-
ly spaced discharge openings, and means on
the lower end of said distributer head adapt-
50 ed to pick up the fuel in said cup and deposit
it on the conical surface of said distributer
head chamber.
2. A rotary oil burner comprising a sup-
porting member, an electric motor thereon,
55 an armature shaft for said motor, a cup
mounted on said motor and having a hub
portion sleeved on the armature shaft there-
of, means for feeding liquid fuel to said cup,
60 and a hollow inverted cone-shaped distributer
head fixed to said armature shaft with its
lower end disposed in said cup, said distributer
head being provided at its upper end with a series of circumferentially spaced dis-
charge openings, a series of finger tubes pro-
65 jecting outwardly from the upper end of
said distributer head, a series of picker blades
on the lower end of said distributer head
- adapted to pick up the fuel in said cup and
deposit it on the conical inner surface of said
distributer head, and a fan rotatable with
70 said distributer head and operating to de-
liver air for combustion at a level below the
level of the discharge ends of said flinger
tubes.
3. A rotary oil burner comprising a sup-
porting member, an electric motor thereon,
75 an armature shaft for said motor, a centrifugal
distributer head rotatable with said shaft,
flinger tubes projecting outwardly from
said distributer head, means for supplying
liquid fuel to said head, a fan rotatable with
80 said shaft and surrounding said distributer
head below the discharge ends of said flinger
tubes, and an axially adjustable tubular shut-
ter interposed between said distributer head
and said fan.
4. A rotary oil burner comprising a sup-
porting member, an electric motor thereon, a
vertical armature shaft for said motor, a cen-
trifugal fuel distributing head rotatable with
85 said armature shaft, a fan rotatable with
said armature shaft and provided with a de-
pending peripheral flange having a series of
openings, and an axially adjustable cylindri-
cal tube disposed concentric to said periph-
90 eral flange with one end inside thereof.
5. A rotary oil burner comprising a sup-
porting member, a hearth ring mounted on
95 said support, an electric motor mounted on
said support concentric with said ring, an
armature shaft for said motor, a fuel dis-
tributing head fixed to said armature shaft,
100 and a fan rotatable with said distributer
head, said fan being provided with a depend-
ing peripheral flange having a series of open-
ings, a cylindrical tube disposed in said
105 hearth ring with its upper end fitting with-
in the peripheral flange of said fan, said tube
being provided with a series of elongated
slots, and pins projecting from the inner face
of said ring into said slots, said slots extend-
110 ing at an oblique angle to the axis of said
tube, whereby said tube when rotated on its
axis will be shifted axially relative to the
peripheral flange of said fan.
6. A rotary oil burner comprising a sup-
porting member, an electric motor thereon,
115 an armature shaft for said motor, a fixed cup
concentric with said armature shaft, means
for feeding liquid fuel to said cup, and a cen-
trifugal distributer head rotatable with
said armature shaft and operating to pick up
120 the fuel in said cup and project it radially
outward, said head having an inverted cone-
shaped recess therein opening into said cup
and a series of blades at the lower edge of
said recess operating to pick up the oil in
125 said cup and deposit it on the walls of said
recess.
7. A rotary oil burner comprising a sup-
porting member, a rotary shaft, a cup mount-
ed on said supporting member and having a
130

hub portion sleeved on the rotary shaft, means for feeding liquid fuel to said cup, and a distributor head fixed to said shaft with its lower end disposed in said cup, said distributor head having an inverted cone-shape chamber therein communicating at its bottom with the interior of said cup, said distributor head chamber being provided at its upper end with a series of circumferentially spaced discharge openings, and means on the lower end of said distributor head adapted to pick up the fuel in said cup and deposit it on the conical surface of said distributor head chamber.

Signed at Detroit, Michigan, this 19 day of July, 1929.
